UNITED STATES PATENT OFFICE.

WILLIAM RICHARD WHITE, OF BLOOMINGTON, ILLINOIS.

DESIGN FOR A GATE-HINGE.

SPECIFICATION forming part of Design No. 32,173, dated January 30, 1900.

Application filed December 16, 1899. Serial No. 740,605. Term of patent 14 years.

To all whom it may concern:

Be it known that I, WILLIAM RICHARD WHITE, a citizen of the United States, residing at Bloomington, in the county of McLean 5 and State of Illinois, have invented and produced a new and original Design for a Gate-Hinge, of which the following is a specification, reference being had to the accompanying drawings, forming a part thereof.

Figure 1 is a perspective view of a hinge embodying my design. Fig. 2 is a side elevation thereof, and Fig. 3 is a top plan view.

The leading feature of my design consists of two flat arms 1 and 2, which are united at 15 one end and diverge at the other. The arm 1 is straight throughout its length and at its free end is provided with downwardly-ex-

tending ears or flanges 4 with registering perforations 5. The arm 2 is bent between its ends to form the diverging portion 6, while 20 the lower end 7 extends downward at about a right angle to the arm 1. The arms 1 and 2 are provided with perforations 8, as shown.

Having described my invention, I claim—

The design for a gate-hinge, substantially 25 as herein shown and described.

In testimony whereof I have signed my name to this specification in the presence of two subscribing witnesses.

WILLIAM RICHARD WHITE.
